UNITED STATES PATENT OFFICE.

BYRON J. IRISH, OF HAGUE, NEW YORK.

BRAKE FOR HORSE-POWERS.

SPECIFICATION forming part of Letters Patent No. 310,436, dated January 6, 1885.

Application filed October 27, 1884. (No model.)

To all whom it may concern:

Be it known that I, BYRON J. IRISH, a citizen of the United States of America, residing at Hague, in the county of Warren and State 5 of New York, have invented certain new and useful Improvements in Brakes for Horse-Powers, of which the following is a specification, reference being had therein to the accompanying drawings.

10 This invention has relation to improvements in automatic brakes to be used on horse-powers; and it consists in the novel construction and arrangement of devices, all as will be hereinafter more fully explained, and particularly pointed out in the claims appended.

15 The annexed drawings, to which reference is made, fully illustrate my invention, in which Figure 1 represents a side view of a horse-power frame, showing my improvement; and 20 Figs. 2, 3, 4, 5, and 6 are detail views.

Referring by letter to the accompanying drawings, A designates one side of an ordinary horse-power, and B is the belt-wheel carrying the belt C.

25 D represents a horizontal lever, which is pivoted at a to the side of the frame A, and the same is provided near its center with a brake-shoe, b, which latter is slotted, as at c, to receive pieces of leather, d, that face the periphery of the belt-wheel, and which receive 30 the wear when the shoe comes in contact with the wheel. To the outer free end of the lever D is pivoted a bar or link, e, the end f of which is pivoted to a vertical lever, g, which in turn 35 is pivoted at its lower end to a bearing on the power-frame, as shown at h. Near the belt-wheel aforesaid, and secured to the side of the frame A, is an angular bracket, i, upon the arm j of which is pivoted an angular lever, k,

to the arm l of which is swiveled a bail, m, 40 through which the belt passes, and to the other arm, n, of said lever k is pivoted one end, o, of a rod, p, which is provided with a hooked end, q, and slides through a staple-eye, r, on the frame aforesaid.

45 It will be seen from the above description and by reference to the annexed drawings that should the belt leave the wheel the weight of the same (the belt) will draw down the bail, thus drawing the rod forward, and 50 by the hook end throw down the vertical lever, and thereby dropping the outer end of the brake-lever, and by its weight the shoe is pressed upon the periphery of the belt-wheel, thus stopping the same immediately and avoiding 55 accidents.

Should it be desired, a weight may be attached to the free end of the brake-lever.

Having described this invention, what I claim, and desire to secure by Letters Patent, 60 is—

1. In a brake for horse-powers, the slotted shoe provided with leather wear-plates, in combination with the lever D and means, as described, for automatically operating the 65 brake, substantially as specified.

2. In a horse-power brake, the combination, with the lever D, belt-wheel, and frame, of the lever g, rod p, bracket i, angular arm k, and loop or bail m, the whole arranged and 70 operating as described, and for the purpose specified.

In testimony whereof I affix my signature in presence of two witnesses.

BYRON J. IRISH.

Witnesses:

CHARLES H. WHEELER,
HORATIO PHILLIPS.
